UNITED STATES PATENT OFFICE.

WALTER DOWNING, OF KEOTA, IOWA.

DESIGN FOR A BUCKLE-FRAME.

SPECIFICATION forming part of Design No. 31,676, dated October 17, 1899.

Application filed August 24, 1899. Serial No. 728,376. Term of patent 14 years.

To all whom it may concern:

Be it known that I, WALTER DOWNING, a citizen of the United States, residing at Keota, in the county of Keokuk and State of Iowa, have invented and produced a new and original Design for Buckle-Frames, of which the following is a specification, reference being had to the accompanying drawings, forming part thereof, and in which—

Figure 1 is a perspective view of a buckle-frame, showing my new design; and Fig. 2 is a sectional view.

The leading or material feature of my design consists in the subject-matter of the accompanying illustrations.

The buckle-frame is formed with the main or base portion A, surmounted at one end by the loop B and connected at such end with the elongated eye C, which lies midway be-

tween lines prolonged from the side bars of the base A, and such eye C is arranged in a plane at right angles to the plane of the base

A. Near the end of the base A opposite the loop B, I provide a cross-bar D, and at such end of the frame the side bars are stepped at 25 E, extend thence at F in lines parallel with the side bars of the frame, and are again stepped at G. Cross-bars E' and G' connect the stepped portions E E and G G. The eye C is connected with the side bars of the base-frame by means of the diverging bars C', which are rounded on their outer sides and merge at such sides in the eye C' and also in the main frame, as shown in the drawings.

Having described my invention, what I 35 claim as new, and desire to secure by Letters Patent, is—

The design for a buckle-frame as herein shown and described.

WALTER DOWNING.
